(57) **CLAIM**

The ornamental design for an arc support, as shown and described.

DESCRIPTION

In a preferred embodiment, the nature of this product is as a wall mountable accessory ring for a towel.

FIG. 1 is a left, top, front perspective view of an arc support according to my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof; and,

FIG. 8 is a front elevational view of an arc support of another embodiment of my new design, the perspective, left side, right side, top, bottom and rear views of this embodiment being mirror images of the respective views shown in FIGS. 1 and 2-7.

The broken line representations of mounting structures in FIG. 7 are for the purpose of illustration only, and form no part of the claimed design.
